(57) **CLAIM**

The ornamental design for a cordless saw, as shown and described.

DESCRIPTION

FIG. 1 is a perspective view of a circular saw according to the present invention;

FIG. 2 is a side perspective view of the circular saw of FIG. 1;

FIG. 3 is a left side view of the circular saw of FIG. 2;

FIG. 4 is a right side view of the circular saw of FIG. 2;

FIG. 5 is a top view of the circular saw of FIG. 2;

FIG. 6 is a bottom view of the circular saw of FIG. 2;

FIG. 7 is an elevated front view of the circular saw of FIG. 2; and,

FIG. 8 is an elevated rear view of the circular saw of FIG. 2.
